Edwin L. Hannum, Westfield, Mass., Lauren E. Seeley, New Haven, Conn., and Edgar C. Desjardins, Westfield, Mass., assignors to The H. B. Smith Company, Incorporated, Westfield, Mass., a corporation of Massachusetts

Application November 27, 1939, Serial No. 306,280

9 Claims. (Cl. 122—228)

This invention relates to an improvement in a boiler and has as its primary object a round boiler comprising two sections joined along a central vertical plane extending from front to back thereof.

Further objects of this invention reside in the provision of a water backed crown sheet overhanging the combustion chamber and made up of two separate sections between which the combustion gases pass from the combustion chamber to the flues through passages defined by registering fins projecting outwardly from the adjacent surfaces of the crown sheet sections, and a flue passage from the combustion chamber, of a baffle by which the normal flow of combustion gases through said flue passage from the chamber to the flue is regulated in accordance with the draft conditions of the boiler, and the proportional distribution of the gases through other passages is secured, of a plurality of nipples by which circulation between the water chambers of the boiler sections is maintained, and of other features which will be more specifically set forth and claimed hereinbelow.

These objects will appear from an examination of the following description of one embodiment of this invention and of the accompanying drawings in which such embodiment is illustrated and in which

Fig. 1 is a perspective view of a complete boiler embodying this invention;

Fig. 2 is a front elevation of such boiler, the casing thereof having been removed but its position indicated by dot and dash lines;

Fig. 3 is a side elevation of the boiler shown in Fig. 2;

Figs. 4 and 5 are rear elevation and plan views, respectively, of such boiler;

Fig. 6 is a view of the boiler in the process of being set up, the two sections being shown separated;

Figs. 7, 8, 9, 10 and 11 are horizontal sectional views taken along such section lines on Fig. 3;

Fig. 12 is a vertical section taken along the line 12—12 of Fig. 3;

Fig. 13 is an elevational view of the upper portion of one section of the boiler;

Fig. 14 is a view similar to Fig. 11 differing therefrom in certain respects; and

Figs. 15 and 16 are illustrations of two forms of baffle plates which might be employed.

The boiler 20 is particularly adapted for use with an oil burner and includes the usual elements, as, for example, a fire pot 21, combustion chamber 22, observation opening 23 and door 24,

burner opening 25 and door 26, clean-out opening 27 and cover 28, flue outlet 29 and stack 30.

The boiler comprises two sections 31 and 32 adapted to be joined in a vertical central plane extending from front to back. The abutting edges are provided with the necessary recesses which, when the boiler is assembled, register to provide the openings 23, 25 and 27 and the outlet 29. These edges are sealed by the provision on the edge of the section 31 of a pair of parallel beads 33 and on the edge of the section 32 a bead 34 which enters the space between the beads 33 in which a suitable cement has been placed in the usual way.

15 The fire-box 21 and combustion chamber 22 are substantially surrounded by water spaces formed in the sections 31 and 32. Each section is provided with a horizontal water space 35 below the fire pot, a semi-cylindrical water leg 36, and a second horizontal water space 37 enclosing the dome of the combustion chamber. In addition each section is also provided with a water leg 38 at the back of the fire pot and a water backed crown sheet section 39 which projects into the combustion chamber.

20 As shown in the drawings the water leg 38 and crown sheet section 39 coact to define and separate from the fire pot and combustion chamber a down draft flue 40 and an upper horizontal flue 41. The fire pot 21 is spaced from the bottom of the boiler by legs 42 to define a bottom horizontal flue 43 connected to the flue 40 by a passage 44 below the water legs 38.

The surfaces of the water legs 38 abut when the sections are assembled and, being provided with beads 45 and 46 similar to the beads 33 and 34, are sealed so that no gases can pass therebetween. The surfaces of the crown sheet sections 39 are, however, spaced apart when the sections are assembled to provide a vertical passage 47 between the combustion chamber 22 and the flues 40 and 41. Fins 48 on these surfaces project into this passage 47 and are in register to define a plurality of separate passageways 49.

45 The fins thus serve to increase the efficiency of the boiler by combing the heat from the fuel not only by the provision of these passageways but also by absorbing the heat and transferring it to the water in the crown sheet sections. It will be noted that these passageways vary in dimensions particularly in length and depth and that they taper outwardly being larger at the exit ends.

40 A fusible plug 52 may be inserted in one of the crown sheet sections as a safety device. Sup-

ported on the upper fins of the sections 39 is a holder plate 53 which carries a baffle 54. The holder plate 53 is so formed that the baffle 54 can project horizontally directly into the vertical path of the gases or vertically into the upper horizontal flue 41 (see Fig. 13). The setting of the baffle is determined by the draft set up in the particular installation, being vertical on average chimneys and horizontal on poor chimneys. The baffle 54 may be solid, as shown in Fig. 15. In place thereof the baffle 55, having its outer edge interrupted by notches 56, may be substituted (see Fig. 16).

Under some conditions the baffle may be omitted or a damper, valve or other similar means may be employed. This feature facilitates a variance of the draft loss depending upon the particular conditions present at each installation. It will be noted that this regulation of the passage through the flue 41 also acts to secure a proportional distribution through the various draft passages from the combustion chamber.

When the sections 31 and 32 are assembled, the water spaces therein are connected by nipples 60, 61 and 62. A tap 63 on the top of the section 32 serves the supply mains and risers to the radiators (not shown). The taps 64 on said section are usually used for accessories such as safety valves or as optional locations for thermometer, aquastat, etc., but might be used for small diameter (1½" or less) steam or hot water lines to the radiators. The return flow enters the spaces through either or both taps 66, if only one tap be used, the other being plugged in the usual way.

Hot water coils 70 may be introduced into the water spaces either through the taps 71 (Figs. 3, 4 and 11) or through one of the taps 72 (Fig. 14). In the second instance the coils pass through the nipple 60 and the tap 72 not used is plugged. In conjunction with the coils 70 an aquastat 73 may be seated in one of the taps 71 or 72 and a reverse action aquastat seated in one of the taps 75. As pointed out above, the taps not used will be plugged.

The sections 31, 32 are secured in position by a plurality of bolts 80 passed through ears 81. At the front of the boiler may be provided a water gauge 82 and a steam gauge 83.

The fire pot 21 includes base sections 85 and 86, side lining plates 87, back lining plate 88 and front lining plate 88^a. The base sections and lining plates may be positioned before or after the sections 31 and 32. Fig. 6 shows the base sections 85 and 86 and the side lining plates 88 positioned before the sections 31 and 32 are assembled, the front and rear lining plates being positioned after the sections are assembled. Usually, however, the opening 25 is of such size that the base sections and lining plates of the fire-box can be positioned after the sections 31 and 32 are assembled. In the outer faces of the plates 87 are formed channels 89 which lead into the bottom horizontal flue 43. Some of the gases are thus carried down the sides and around the bottom of the fire pot, thereby quickly heating and increasing the efficiency thereof.

While one embodiment of this invention is adapted for use with an oil burner, it will be understood that the invention is not limited thereto and that other embodiments thereof adapted for use with oil or other fuel may be made without departing from the spirit and scope of the invention as set forth in the following claims.

We claim:

1. A boiler having a fire pot, a combustion chamber, a stack, a down draft flue, a horizontal flue, said down draft flue leading to said stack and said horizontal flue leading from said combustion chamber to said down draft flue whereby said flues connect said combustion chamber with said stack and a plurality of connected water spaces, said spaces including a water leg between said fire pot and said down draft flue, and a water backed crown sheet which projects into said combustion chamber and separates said chamber from said down draft and horizontal flues.

15 2. A boiler having a fire pot, a combustion chamber, a stack, a down draft flue, a horizontal flue, said down draft flue leading to said stack and said horizontal flue leading from said combustion chamber to said down draft flue whereby 20 said flues connect said combustion chamber with said stack and a plurality of connected water spaces, said spaces including a water leg between said fire pot and said down draft flue, a water backed crown sheet which projects into said combustion chamber and separates said chamber from said down draft and horizontal flues, and means for varying the draft conditions at the horizontal flue.

30 3. A boiler having a fire pot, a combustion chamber, a stack, a down draft flue, a horizontal flue, said flues connecting said combustion chamber with said stack and a plurality of connected water spaces, said spaces including a water leg between said fire pot and said down draft flue, 35 water backed crown sheets between said combustion chamber and said down draft and horizontal flues, and a plurality of passageways between said crown sheets through which gases may escape from said combustion chamber into said down draft flue.

40 4. A boiler having a fire pot, a combustion chamber, a stack, a down draft flue, a horizontal flue, said flues connecting said combustion chamber with said stack and a plurality of connected 45 water spaces, said spaces including a water leg between said fire pot and said down draft flue, and a water backed crown sheet between said combustion chamber and said down draft and horizontal flues, said crown sheet being in two sections spaced apart vertically to provide passageways through which gases may escape from said combustion chamber into said down draft and horizontal flues.

55 5. A boiler having a fire pot, a combustion chamber, a stack, a down draft flue, a horizontal flue, said flues connecting said combustion chamber with said stack and a plurality of connected water spaces, said spaces including a water leg between said fire pot and said down draft flue, 60 and a water backed crown sheet between said combustion chamber and said down draft and horizontal flues, said crown sheet being in two sections spaced apart vertically to provide passageways through which gases may escape from said combustion chamber into said down draft and horizontal flues, and fins on the adjacent surfaces of the crown sheet sections which form said passageways, which fins register to define a plurality of separate passageways.

6. A boiler having a fire pot, a combustion chamber, a stack, a down draft flue, a horizontal flue, said flues connecting said combustion chamber with said stack and a plurality of connected water spaces, said spaces including a water leg between said fire pot and said down draft flue,

and a water backed crown sheet between said combustion chamber and said down draft and horizontal flues, said crown sheet being in two sections spaced apart vertically to provide passages through which gases may escape from said combustion chamber into said down draft and horizontal flues, and fins on the adjacent surfaces of the crown sheet sections which form said passages, which fins register to define a plurality of separate passageways, and a baffle carried by said crown sheet and projecting into the stream of gases flowing from the combustion chamber past the end of the crown sheet and through the horizontal flue.

7. A boiler having a fire pot, a combustion chamber, a stack, a down draft flue, a horizontal flue, said flues connecting said combustion chamber with said stack and a plurality of connected water spaces, said spaces including a water leg between said fire pot and said down draft flue, and a water backed crown sheet between said combustion chamber and said down draft and horizontal flues, said crown sheet being in two sections spaced apart vertically to provide passages through which gases may escape from said combustion chamber into said down draft and horizontal flues, and fins on the adjacent surfaces of the crown sheet sections which form said passages, which fins register to define a plurality of separate passageways, and a baffle carried by said crown sheet and projecting into the stream of gases flowing from the combustion chamber past the end of the crown sheet and through the horizontal flue, said baffle extending horizontally into the path of the gases past the end of the crown sheet.

8. A boiler having a fire pot, a combustion chamber, a stack, a down draft flue, a horizontal flue, said flues connecting said combustion chamber with said stack and a plurality of connected 40

water spaces, said spaces including a water leg between said fire pot and said down draft flue, and a water backed crown sheet between said combustion chamber and said down draft and horizontal flues, said crown sheet being in two sections spaced apart vertically to provide passages through which gases may escape from said combustion chamber into said down draft and horizontal flues, and fins on the adjacent surfaces 5 of the crown sheet sections which form said passages, which fins register to define a plurality of separate passageways, and a baffle carried by said crown sheet and projecting into the stream of gases flowing from the combustion chamber past the end of the crown sheet and through the horizontal flue, said baffle extending vertically into the horizontal flue into the path of the gases as they round the end of the crown sheet.

9. A boiler having a fire pot, a combustion chamber, a stack, a down draft flue, a horizontal flue, said flues connecting said combustion chamber with said stack and a plurality of connected water spaces, said spaces including a water leg between said fire pot and said down draft flue, and a water backed crown sheet between said 20 combustion chamber and said down draft and horizontal flues, said crown sheet being in two sections spaced apart vertically to provide passages through which gases may escape from said combustion chamber into said down draft and horizontal flues, and fins on the adjacent surfaces of the crown sheet sections which form said 25 passages, which fins register to define a plurality of separate passageways, and means in said horizontal flue for varying the flow of gases therethrough and thereby proportionately distributing 30 the flow of gases through the various passages.
